Primary Examiner — Leanne Was-Englehart

(57) **CLAIM**

The ornamental design for a baby fence assembly, as shown and described.

DESCRIPTION

FIG. 1 is a perspective view of a first component of a baby fence assembly showing my new design, shown separately for ease of illustration;

FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view of a second component of the baby fence assembly showing my new design;
FIG. 10 is another perspective view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a top plan view thereof;
FIG. 16 is a bottom plan view thereof;
FIG. 17 is a perspective view of a third component of the baby fence assembly showing my new design;
FIG. 18 is another perspective view thereof;
FIG. 19 is a front elevational view thereof;
FIG. 20 is a rear elevational view thereof;
FIG. 21 is a left side elevational view thereof;
FIG. 22 is a right side elevational view thereof;
FIG. 23 is a top plan view thereof;
FIG. 24 is a bottom plan view thereof;
FIG. 25 is a perspective view of a fourth component of the baby fence assembly showing my new design;
FIG. 26 is another perspective view thereof;
FIG. 27 is a front elevational view thereof;
FIG. 28 is a rear elevational view thereof;
FIG. 29 is a left side elevational view thereof;
FIG. 30 is a right side elevational view thereof;
FIG. 31 is a top plan view thereof;
FIG. 32 is a bottom plan view thereof; and,
FIG. 33 is a perspective view of the baby fence assembly where the baby fence assembly is in a configuration of use. The broken lines in FIGS. 1-32 depict portions of the baby fence assembly that form no part of the claimed design. The broken lines in FIG. 33 depict environment that forms no part of the claimed design.
